UNITED STATES PATENT OFFICE.

GEORGE K. DAVOL, OF SAN FRANCISCO, CALIFORNIA, ASSIGNOR TO CHARLES A. BROWN, OF HINSDALE, ILLINOIS.

INTERNAL-COMBUSTION ENGINE.

Application filed August 6, 1921. Serial No. 490,218.

To all whom it may concern:

Be it known that I, GEORGE K. DAVOL, a citizen of the United States, residing at San Francisco, in the county of San Francisco and State of California, have invented a certain new and useful Improvement in Internal-Combustion Engines, of which the following is a full, clear, concise, and exact description, reference being had to the accompanying drawings, forming a part of this specification.

My invention relates to internal combustion engines and has for one of its objects the production of a simple improved engine of the fuel injection type, in which the fuel can be efficiently atomized and injected into the cylinder or combustion chamber by means of compressed air, and which at the same time shall be free from undue complication of mechanism.

While the essential features of my invention can be embodied in forms of engines operating on the four stroke cycle or on the two stroke cycle, in the embodiment of the invention herein disclosed, operation of the four stroke cycle is assumed, and I have not thought it necessary to point out in detail the manner of applying the features of the invention to an engine operating on the two stroke cycle as such application is obvious.

My invention has particularly to do with an engine in which a separate air compressing cylinder is provided for each working cylinder of the engine, for the purpose of providing injection air, or compressed air for the injection of the fuel into the working cylinder or combustion chamber.

In the accompanying drawings:

Figure 1 is a sectional view of the working and compressing cylinder of an engine embodying the principles of my invention.

Figure 2 is a sectional view of two adjacent compressing cylinders taken at right angles to the section shown in Figure 1.

Figure 3 is an enlarged sectional view of the fuel injecting valve.

Figure 4 is an outside view of the end of the fuel injecting valve, and

Figures 5 and 6 are cross sections of the fuel injecting valve taken on the line 5-5 and 6-6 of Figure 3 respectively.

In the embodiment of my invention selected for illustration, a main cylinder casting 1 is provided, in which are formed a working cylinder 2 and a compressing cyl-

inder 3. A working piston 4 connected with the end of connecting rod 5 reciprocates in the working cylinder, and a compressing piston 6 similarly connected by the rod 7 to a crank on the cam shaft of the engine, reciprocates in the compressing cylinder. Figure 2 shows two adjacent compressing pistons 6 of a multi-cylinder engine, connected by rod 7 to the cam shaft 8. Above the main cylinder casting is a cylinder head 9, and above the head, a valve tapped frame 10 and a final cover 11 are placed. The cylinder casting 1, head 9, tappet carrying frame 10, and cover 11 are all secured together by studs or bolts (not shown).

A spring held air admission valve 12 is carried in a cage or seat 13 in an opening formed in the head 9. This cage 13 is held down against the pressure within the cylinder 3 by a screw collar or gland 14 bearing 70 on packing 15 to force the cage against a seat or footing 16. An inlet passage or manifold 17 supplies air to all the working cylinders of the engine. The main inlet valve 18 of the working cylinder 2 is shown 80 in dotted lines in Figure 1 as it lies behind the section taken. This inlet valve 18 is operated by the tappet 19 pivoted on the shaft 20 and deriving motion from the tappet rod 21. Figure 2 shows the rod 21 and tappet 19 for the operation of both inlet and exhaust valve of two adjacent working cylinders.

The inlet valve 18 is supplied with air from the passage 17 by a branch passage 90 indicated by dotted lines 22 (see Figure 1). A passage or opening 23 allows air to flow from the passage 17 through passages in the valve case 13 to the air admission valve 12 and through the same into the compressing cylinder 3 on the suction stroke. In this manner both the working cylinders and the air compressing cylinders are supplied with air from one passage or manifold 17 and so are equally effected by any throttling or alteration of the density of the air within the passage 17.

In Figure 1 I have shown the passage 17 connected to an intake pipe 17' in which is pivotally mounted a throttle 17'' of any suitable construction. The throttle 17'' is adapted to control the charge admitted through the passage 17 in a manner well known to those skilled in the present art. Obviously, as will become more apparent as 110

the present description progresses, by varying the mass of the fluid entering the passage 17 the mass of both the branch charge and the main charge coming from the passage 17 will be varied without varying the ratio between them.

The cam shaft 8 is carried in bearings 24 and on each side of each of the cranks which operate the compressing pistons carries a cam 25. These cams operate sliding blocks 26 suitably held in guides, which blocks in turn operate the tappet rods 21. By positioning the compressing cylinder for each main cylinder between the valve actuating mechanism for that cylinder, a very compact, symmetrical, and convenient arrangement of the assembled parts is obtained.

At the end of the compression stroke of 20 the compression pistons, in which position the compression piston 6 is shown in Figure 1, there is still left a considerable clearance space within the compression cylinders, within which the air entrapped and compressed is held. This body of air compressed within this clearance space of any one compression cylinder is used to atomize and inject fuel into the corresponding working cylinder or combustion chamber.

30 In using the term "cylinder" in this description and in the claims which follow I intend to designate the chamber which, together with the piston fitting a portion of it, sustains the pressure of air or gases held, 35 compressed or expanded within it, whether such chamber be actually of cylindrical form or other form. The extension of the compressing cylinder into the cylinder head 9 I therefore refer to as a part of the compression cylinder, or as the clearance space of the compression cylinder, although its form need not be cylindrical.

Passing through the clearance space is 45 an injection valve body 27 having a central bore 28 and a fuel nozzle 29 in said bore. This fuel nozzle is secured to the body by its end flange and screws 30, which screws pass through the flange and the connector 31 and enter the body 27. Passage of air 50 from cylinder 3 to bore 28 is suitably controlled by a delivery valve 33 screwed at one end to the body 27 and normally closing port 32.

A recessed cap 34, (see Figure 3) is 55 screwed to the inner end of the body 27, and on its external end bears against and makes gas tight contact with the end of the hole formed in the cylinder head 9 to receive it. An extension passage 35 connects with a passage 36 opening into the working cylinder 2, within which passage is an adjustable needle 37. The shank of this needle fits passage 36 and is threaded for screw adjustment therein, as shown in Figure 1, to adjust the conical inner end of the needle relative to the

contracted inner end of the passage 36 and vary the area of the final orifice communicating with the cylinder 2.

Within the recessed cap 34 is a valve stop 38 (see Figure 3) having an axial bore and small radial holes 39. The end of the body entering the recessed cap 34 forms a seat for the check valve 40, which loosely fits the bore of the recessed cap 34 and plays between its seat and the end of the valve 70 stop 38. The valve is provided with small holes near its edge, through which holes the air and atomized fuel may pass when the valve is off its seat.

The injection valve body 27 is held in 80 place and forced in against the head 9 by gland 41 secured by studs to the head 9, gland ring 42 and packing 43 bearing against the flange 44. Gland 41 (see Figure 4) has an inverted U-shape to permit extension of the connector 31 for connection to the fuel pipe 45. The fuel is forced through this pipe 45 at the proper time and in proper quantity by any suitable means, and passes through the passage 46 and small orifices 85 47 in the nozzle 29 out into the annular space 90 surrounding the inner end of the nozzle.

Two small plungers 48 having enlarged heads pass through the body 27 and underlie the free end of valve 33, the body being 95 drilled and suitably recessed for the plunger heads, so that the plungers rest free from contact with the valve. The inner face of the compressing piston 6 is recessed by a two diameter hole for the accommodation of a 100 tappet 49. This tappet is forced upward by the strong spring 50 surrounding its shank. The tappet is held down in adjustable position against the action of the spring, by the adjusting and retaining 105 screw 51.

At the end of the up stroke of piston 6, the tappet 49 comes into contact with and lifts the lower projecting end of the plungers 48, which in turn lifts the valve 33 off 110 its seat, permitting the air compressed within the clearance space above the piston to rush through the port 32 into the annular space surrounding the nozzle 29. There the air picks up the fuel previously deposited and carries it through the passage 28, valve 40, hole 39, and passages 35 and 36 into the working cylinder 2, atomizing the fuel by 115 its velocity through these various passages and through the final atomizing orifice surrounding the point of the needle 37.

It will be noted that one side of the top of the tappet is beveled off or inclined. This is an important feature as it enables the valve body 27 to be inserted in place 120 even when the piston 6 is at the top of its stroke, as the plungers 48 striking the inclined side of the tappet as the body is pushed into place, slide up the incline into 125 the position shown in Figure 3.

The air compressed by piston 3 expands again in the clearance space in which it was originally compressed and the resultant cooling tends to lessen the importance of water jacketing this part of the device.

With the direction of the jet of atomized fuel and air entering the working cylinder 2 or with the timing of this injection, my present invention is less essentially concerned. The entering jet may be arranged to produce an intimate mixing of the entire charge within the working cylinder as in the arrangement disclosed by the drawings or it may be so introduced as to produce a stratified charge.

The timing of fuel injection is regulated by the relative positions of the air compressing crank of the cam shaft 8 and the crank of the working piston, which position may be chosen to suit the timing desired. Thus the invention may be embodied in an engine in which the fuel is injected into the working cylinder before or during the compression stroke and ignited by an electric spark, or it may be embodied in an engine injecting the fuel at or near the end of the compression stroke of the working piston, ignition being obtained through the heat of compression or otherwise.

When the invention is embodied in an engine injecting the fuel previous to or during the early part of the compression stroke and the entire contents of the cylinder is intimately mixed, a certain limited range of variation of the proportion of fuel to air is required, and this may ordinarily be maintained with varying loads through throttling the air supply to the intake passage or manifold 17, and simultaneously adjusting the amount of fuel supplied. When the main air supply is so throttled to any considerable extent, it may become under certain conditions a matter of importance to also reduce the amount of air used for injecting and atomizing the fuel. By drawing the injection air from the same source, passage 17, as that supplying the working cylinder, this reduction is automatically taken care of.

The direction of jet and the form of the part on which it impinges may be chosen so as to promote an extreme turbulence of the cylinder contents, and the surface on which the jet first impinges may be so designed and arranged as to be maintained through the heat of combustion above a certain minimum temperature, and at the same time be maintained below a certain maximum temperature by the cooling action of the impinging jet of atomized fuel and air. Such a surface at the proper temperature will act to assist in vaporizing the fuel previous to ignition.

Without further elaboration, the foregoing will so fully explain the gist of my invention, that others may, by applying cur-

rent knowledge, readily adapt the same for use under various conditions of service. It will, for instance, be obvious, that plungers 48 might be made without heads and carried on the piston, or that an entirely different valve might be substituted for the flap valve 33 illustrated as the preferred form of this part of the device. These and many other modifications and alterations will readily occur to those skilled in the art and may obviously be made without eliminating certain features which may properly be said to constitute the essential items of novelty involved in my invention, which items are intended to be defined and secured to me by the following claims.

I claim:

1. In an internal combustion engine of the fuel injection type, a working cylinder, a compression cylinder, a piston reciprocating in said compressing cylinder, a port for delivering air from said compressing cylinder, a valve closing said port and opening against the pressure in said compression cylinder, and means for operating said valve from the movement of said compression piston.

2. In an internal combustion engine, a working cylinder, a piston and cylinder for compressing air to inject fuel, a delivery valve located entirely within said last mentioned cylinder, and an operative connection between said valve and said piston.

3. In an internal combustion engine, a working cylinder, a second cylinder for compressing air to inject fuel, a delivery passage connecting with said compressing cylinder, a valve for closing said passage, a piston moving in the compressing cylinder, and means operated by contact with said piston for opening said valve against the pressure in said cylinder.

4. In an internal combustion engine, a working cylinder, a second cylinder for compressing air to inject fuel, a delivery passage leading from said compressing cylinder, a flat flexible valve overlying said passage to cover the same, a piston in said compressing cylinder, and means providing an operative contact connection between said valve and said piston.

5. In an internal combustion engine, a working cylinder, a second cylinder for compressing air to inject fuel, a delivery valve holding body passing through the clearance space of said compressing cylinder, a passage leading from said valve holding body to said working cylinder, a valve supported by and seated on said valve holding body, a piston in said compressing cylinder, and means for operating said valve through contact with said piston.

6. In an internal combustion engine, a working cylinder, a second cylinder for compressing air to inject fuel, a delivery valve

- holding body within the clearance space of said compressing cylinder, a flat flexible valve seating on said body, plunger means passing through said body to act against the seating face of said valve, and a piston reciprocating in said compressing cylinder, said piston making contact with said plunger means.
7. In an internal combustion engine, a working cylinder, a second cylinder for compressing air to inject fuel, a delivery valve holding body having a passage therein, said passage communicating with said working cylinder, and a non-return check valve carried by said delivery valve holding body and placed in said passage, said body extending into the compression space of said compression cylinder.
8. In an internal combustion engine, a working cylinder, a cylinder for compressing air to inject fuel, a delivery valve holding body having a passage therein, said body passing through the clearance space of said compressing cylinder, and a non-return check valve placed in said passage.
9. In an internal combustion engine, a working cylinder, a cylinder for compressing air to inject fuel, a delivery valve holding body having an axial passage therein and passing through the clearance space of said compressing cylinder, and a source of fuel supply connecting with the outer end of said axial passage, the inner end of said axial passage communicating with said working cylinder.
10. In an internal combustion engine, a working cylinder, a cylinder for compressing air to inject fuel, an air inlet passage supplying air to said working cylinder, an inlet valve opening into said compressing cylinder, and a connecting passage between said inlet valve and the passage supplying the said working cylinder.
11. In an internal combustion engine, a working cylinder, a cylinder for compressing air to inject fuel, a piston in said compressing cylinder, an adjustable member on the inner face of said piston, and delivery valve mechanism open to the interior of said compressing cylinder and arranged to be unseated by said adjustable member.
12. In an internal combustion engine, a working cylinder, a cylinder for compressing air to inject fuel, a passage parallel to the axis of and opening into the working cylinder for delivering fuel thereto, and a delivery valve holding body passing in open connection with the clearance space of said compressing cylinder, said body having an axial passage connecting with said first mentioned passage.
13. In an internal combustion engine, a working cylinder, a cylinder for compressing air to inject fuel, a passage parallel to the axis of and opening into the working cylinder for delivering fuel thereto, and a delivery valve holding body passing through the clearance space of said compressing cylinder, said body having an axial passage connecting with said first mentioned passage.
14. The method of controlling an internal combustion engine of the injection type, comprising compressing an injection air charge for each main charge, taking both charges from a common conduit, and throttling the conduit.
15. In an internal combustion engine of the fuel injection type, a compressing cylinder and piston, and a delivery valve structure inside the clearance space of said cylinder.
16. In an internal combustion engine of the fuel injection type, a compression cylinder and piston, and a delivery valve structure inside the clearance space of said cylinder, said valve being automatically operated by contact with said piston.
17. In an internal combustion engine, a working cylinder, an injection conduit leading thereto, means defining a space surrounding a portion of said conduit, means for compressing air into said space, a lateral port in the portion of said conduit passing through said space, and a delivery valve controlling said port.
18. In an internal combustion engine, two cylinders, a valve in one of the said cylinders and an injection conduit passing through the clearance space of one cylinder communicating with the said cylinder through the said valve, and opening into the other cylinder.
19. In an internal combustion engine, two cylinders, an injection conduit passing through the clearance space of one cylinder and opening into the other cylinder, means for depositing liquid fuel at an intermediate point in said conduit, and means for flowing air through said conduit past said point to inject said fuel into the cylinder.
20. The method of controlling an internal combustion engine of the injection type, comprising independently compressing an injection air charge for each main charge, and varying the mass of both charges without varying the ratio between them.
21. In an internal combustion engine, a working cylinder, a second cylinder for compressing air to inject fuel, a delivery passage leading from said compressing cylinder, and a flat flexible valve overlying said passage to cover the same.
- In witness whereof, I hereunto subscribe my name this second day of August, 1921.

GEORGE K. DAVOL.
